W. A. EVANS

ELECTRICAL CONNECTER

Filed Oct. 8, 1921

FIG. 1

FIG. 2.

FIG. 3.

Inventor:
William A. Evans

by W. Beatty, Atty.

UNITED STATES PATENT OFFICE.

WILLIAM A. EVANS, OF RIDGEWOOD, NEW JERSEY, ASSIGNOR TO WESTERN ELECTRIC COMPANY, INCORPORATED, OF NEW YORK, N. Y., A CORPORATION OF NEW YORK.

ELECTRICAL CONNECTER.

Application filed October 8, 1921. Serial No. 506,265.

To all whom it may concern:

Be it known that I, WILLIAM A. EVANS, a citizen of the United States, residing at Ridgewood, in the county of Bergen, State of New Jersey, have invented certain new and useful Improvements in Electrical Connecters, of which the following is a full, clear, concise, and exact description.

This invention relates in general to electrical connecting devices and more particularly to devices of the type wherein electrical connections are established by means of plugs and jacks.

It is the object of this invention to provide a structure for a plug connector having contact members adjustable in their lateral spacing, which is simple, inexpensive, and in which the parts are easily removable.

This invention is an improvement of the type of plug described in C. W. Lowe Patent No. 1,309,253, issued July 8, 1919, and provides a simplified construction to accomplish the above object.

The invention in its preferred form is a plug commonly termed in telephone practice an operator's plug, and comprises a pair of plug fingers each provided with a rectangular block of insulating material, which blocks fit adjustably within a casing or shell.

The opposite edges of the insulating blocks are grooved to engage turned-in ends of a U-shaped yoke which also fits within the casing. An aperture is provided through the casing and the yoke for the introduction

of conductors connecting with the contacts on the plug fingers, and through this aperture a bushing screws into the yoke, holding the yoke within the casing and the plug fingers within the yoke.

The invention will be more clearly understood by reference to the following description of one form which the invention may assume in practice, taken in connection with the accompanying drawing, in which Fig.

1 is a top view of the plug assembly; Fig. 2 is a longitudinal cross section; and Fig. 3 is a view of the various parts of the plug indicating the method of assembling. In the figures similar reference characters refer to similar parts.

Referring to the drawing, 1 and 2 are a pair of plug fingers of the type ordinarily used for telephone switchboard plugs. They

are each provided with a central conductor 3 which terminates at one end in a tip contact and at the other end in a threaded portion to form a suitable binding post 4; and a sleeve contact 5 which is threaded at one end and provided with a nut 6. A shoulder 7 is provided on each of the plug fingers 1 and 2. On each of the plug fingers is fastened a block of insulating material 8. The insulating blocks 8 are clamped on the plug fingers between the shoulders 7 and the nuts 6. On their opposite edges the blocks 8 are grooved to be engaged by the bent-in edges 10 of a U-shaped yoke 9 to allow free lateral movement but at the same time preventing the longitudinal movement of the plug fingers. Yoke 9 fits within a shell or casing 13 and preferably conforms with the inner surface thereof.

The yoke 9 is provided with a threaded aperture 16 which registers with a corresponding aperture in the rear of the casing 13. A threaded bushing 11 passes through the aperture in the rear of the casing 13 and threads into the aperture 16 in the yoke 9, thereby holding the various parts within the shell.

The bushing 11 also provides a means for introducing the conductor cord 12 into the interior of the plug shell so that its conductors may be connected with binding post 4 and a suitable lug 14 associated with the contacting portions 3 and 5 respectively of the plug fingers.

The strain relieving portion of the cord 12 is attached to a post 15 which fits into apertures in each side of the yoke 9. The outline of the insulating blocks 8 conforms generally to the shape of the opening in the casing 13, but allowance is made in their outline to permit slight lateral movement. The plug fingers are, therefore, adjustable within limits and adapt themselves to any slight inaccuracy in the distance between the centers of the jacks (not shown) into which they are adapted to be inserted.

From the above description it will be seen that the plug may be completely taken apart for repair of the cord connections or replacement of defective parts by merely removing the bushing 11 which is a very simple operation and requires very little time to perform.

What is claimed is:

A connecting plug comprising a pair of plug fingers, a casing for the plug fingers, an insulating block supported on each plug finger and grooved on opposite edges, a yoke cooperating with the grooves in the blocks to hold the plug fingers against longitudinal

movement and to permit lateral movement thereof, and a threaded bushing fastening the yoke within the casing and providing access therethrough. 10

In witness whereof, I hereunto subscribe my name this 6th day of October A. D., 1921.

WILLIAM A. EVANS.
